UNITED STATES PATENT OFFICE.

LUCIAN W. BUGBEE, OF INDIANAPOLIS, INDIANA, ASSIGNOR TO ONEPIECE BIFOCAL LENS COMPANY, OF INDIANAPOLIS, INDIANA, A CORPORATION.

LENS-POLISHING MACHINE.

1,366,159.

Specification of Letters Patent. Patented Jan. 18, 1921.

Application filed March 6, 1919. Serial No. 281,035.

To all whom it may concern:

Be it known that I, LUCIAN W. BUGBEE, a citizen of the United States, and a resident of Indianapolis, county of Marion, and State of Indiana, have invented a certain new and useful Lens-Polishing Machine; and I do hereby declare that the following is a full, clear, and exact description thereof, reference being had to the accompanying drawings, in which like numerals refer to like parts.

The object of this invention is to improve, facilitate and cheapen the polishing of toric, meniscus and other lenses, so as to improve the polished surfaces of such lenses and reduce the cost of polishing the same.

One feature of the invention consists in the combination of a spotting wheel with the spots cut in the metal surface thereof, whereby the lens blanks can be secured thereto with the edges mounted directly on and in engagement with the metal surface of the wheel, the blanks being secured thereto by pitch or other adhesive material between the middle portions of the blanks, and means for applying to the outer surface of the blanks, when so mounted on said spotting wheel, a plurality of polishers made of, or covered with pitch. This construction will polish the blanks rapidly and without the heat, generated by the friction of the polishers on the lens blanks, softening the pitch so as to interfere with the successful operation.

Means for applying a constant stream of rouge and water to the pitch polishers is also preferably provided, for insuring that the pitch of the polishers shall remain sufficiently hard to polish successfully.

Another important feature of the invention consists in the means substantially herein shown for causing a differential lateral or variable movement or feed of the plurality of polishers across the lens blanks transversely of the wheel, during the polishing operation. To that end a rocking frame is provided, with arms pivoted to the upper end and arms pivoted to the lower end, and these arms pivotally mounted with the polishing holders, and yielding means for drawing said arms and polishing holders toward the spotting wheel.

Another feature of the invention consists in a cam construction substantially as here-

in set forth for operating said rocking frame, and still another and very important feature of the invention consists in different means for rotating the spotting wheel and for operating said cam and rocking frame for causing the differential movement of the polishers. In this invention this is accomplished by securing the cam to the side of a pulley loosely mounted on the shaft which drives the spotting wheel.

Another feature of this invention consists in driving the said cam at a slower or different speed than the speed of the shaft which drives the spotting wheel.

The full nature of the invention will be understood from the accompanying drawings and the following description and claims:

In the drawings, Figure 1 is a side elevation of the polishing machine. Fig. 2 is a front elevation of the machine. Fig. 3 is a plan view of a cam disk. Fig. 4 is a diagram of the cam surface of the cam. Fig. 5 is a plan view of the spotting wheel with the lenses mounted thereon. Fig. 6 is a section therethrough. Fig. 7 is a section of a portion of the wheel on the line 7-7 of Fig. 6. Fig. 8 is a transverse section of a portion of the wheel on an enlarged scale. Fig. 9 is a portion of Fig. 7 on an enlarged scale. Fig. 10 is a central section through a pitch polisher.

There is shown in the drawings herein a machine having a main frame 10, which carries a driving shaft 11 having a driving pulley 12, which is driven by some suitable source of power, and a pair of pulleys 13 and 14 for transmitting power through the belts 16 and 17 to the mechanism above. The pulley 14 is smaller than the pulley 13.

Upon the main frame there is another frame having a base 115 with two upright portions 116 and 117, which carry horizontal bearings 18 and 19 on their upper ends and in which the shaft 20, which drives the spotting wheel, is mounted. The shaft 20 is driven by the belt 15 through a driving pulley 21 secured on the shaft. There is also a driving pulley 27 loosely mounted on the shaft, which is driven by the belt 16 at a slower speed than the pulley 21. This difference in speed may be effected by reducing the diameter of either pulley 14 or pulley 27 as compared with the corresponding pulleys 13 and 21.

The cam 30 is secured to the side of the pulley 27. It is annular in form and projects laterally from the side of the pulley and is provided with a series of cam elevations and depressions successively graduated, as shown in Figs. 1, 3 and 4. The series of depressions and elevations of the cam increase at one side or for 180 degrees and from the lowest to the highest point, 10 and the other side diminishes gradually from the highest to the lowest elevation. The lowest depression is diametrically opposite the highest elevation and the other depressions are opposite corresponding elevations. 15 In other words the construction of the cam is such that as said surfaces are engaged by the diametrically opposite pair of rollers 35 of the rocking frame 36, the rotation of the cam will cause the rocking of said frame to and fro. There are shown in the drawings, see Figs. 1, 3 and 4, three elevations and three depressions, A, E, and C and three depressions F, D, and B graduated, and they cause the rocking movement 20 indicated by dotted lines in Fig. 4. The rollers 35 simultaneously engage the highest elevation A and the lowest depression D, and then the highest depression F and the intermediate elevation C, and then the lowest elevation C and the highest elevation B, and this order is repeated as the cam rotates. 25

The rocking frame 36 is rectangular in shape as shown in Fig. 2 and is fulcrumed at its opposite sides on pins 37 which extend outwardly from the bearing 19. To the upper and lower ends of the frame 36 bars 40 are pivoted, which bars extend forward and at their outer ends carry a widened head 41 with vertical guide plates thereon, which have a laterally projecting screw 42. A vertical pin 44 is secured in the outer end of each of said arms which loosely engages a recess or socket in the polisher 45. The polisher has two laterally disposed pins 47 pivotally connected with each end of the polisher holder 147, which have vertical slots between which the screws 42 loosely extend. The polisher 45 shown in Fig. 10 has a polishing surface 46 made of pitch. 50

The spotting wheel 50 is secured on the shaft 20 so as to be rotated thereby. Upon the surface of said wheel lens blanks 51 are secured. The wheel has a convex peripheral surface so as to hold lenses adapted to have plus outer surfaces. 55

The upper and lower bars 40 are drawn toward each other by springs 52, one on each side of the machine, for the purpose of 60 constantly and yieldingly forcing the polishers down upon the lens blanks upon the wheel 50 while the latter is rotated and whereby the polishing results, the speed thereof depending upon the strength of the 65 springs 50.

In order to explain more fully the complete nature of this invention and its utility, an explanation will be made of one form of the spotting wheel and the manner of mounting the lens blanks thereon. This is 70 illustrated in Figs. 5 to 9, and has been particularly designed for use in grinding and polishing toric lenses. After the lens blanks are mounted on the wheel, the same wheel and blanks are put first in a grinding machine and thereafter in the polishing machine so that the lenses are ground and polished without removing them from the blank holder. 75

The wheel 50 is a metal wheel of such diameter as to give the periphery thereof a curvature of substantially six diopters. Then there is cut in the metal surface of the wheel a succession of substantially rectangular spots or seats 60 for the lens blanks 51. All 80 of these spots are exactly alike and equidistant from the center of the wheel and truly balanced and have a uniform standard of curvature. The concave sides of the blanks are finished and polished and then 85 secured upon the wheel, on said spots or seats, so that the borders of the glass will rest slightly upon the iron of the wheel and thus be mounted thereon with absolute accuracy. A thin layer of adhesive material 90 61 is placed in the concave surface of the lens, whereby it adheres into the place on which it has been mounted on the wheel, substantially as shown. The blanks are thus 95 secured properly in place equidistant from the center and truly balanced on the wheel and with their margins abutting each other so as to present a solid and substantially continuous surface on the wheel after they are mounted. The wheel is then placed in 100 the grinding machine and the outer surfaces of said blanks are ground. Then the wheel 105 is removed from the grinding wheel and placed in the polishing machine, as shown in Fig. 1. 110

It is observed that as the machine operates, the wheel 50, carrying the lens, will rotate and the polishing button or tools 45 and 46 will engage their outer surfaces and polish them. Since the lenses are mounted 115 directly on the metal of the wheel, pitch can be used on the polishing buttons and a plurality of the polishers may be employed without creating sufficient friction to soften the pitch which secures the lenses to the 120 wheel 50, or the pitch on the polishing buttons or tools. However, in operation, a stream of water and rouge is supplied to keep these parts as cool as possible. 125

As the machine operates, the rocking 125 frame 36 and the bars 40, as they are actuated by the cam 30, will constantly move the polishers crosswise of the polishing wheel 50, to limited extents. Since there are two polishers shown here on opposite sides of 130

the wheel 50, when the parts are in the position shown in Fig. 1, the upper polisher would operate on the right-hand portion of the set of lenses and the lower polisher on 5 the left-hand portion. The lateral shifting of these polishers is not entirely across the wheel, but only partially. When the cam is given a one-third turn, the upper wheel 35 will run into a depression, while the lower 10 wheel will run on an elevation, but these depressions and elevations increase and diminish in height in succession so that about one-third of the time, the polishers may be said to be diagonally disposed, as in 15 Fig. 1, for about one-third of the time, they are more centrally disposed, and for about another third of the time, they are oppositely arranged, as compared with their diagonal position in Fig. 1, that is, the upper 20 polisher will be nearer the left hand edge of the wheel 50.

In order to be sure that the pitch 46 on the polisher 45 remains hard and to reduce the head of all the parts caused by friction 25 during the polishing, a constant stream of rouge and water is discharged on the periphery of the wheel through the tube 60 leading from a receptacle 61 secured to the right hand side of the bar 19. 30 The invention is not limited to the number of polishers or the manner in which they are formed, as three or four instead of two could be used, but this invention enables a plurality of polishing elements to be employed 35 so that the polishing of these lenses is greatly facilitated as compared with methods heretofore employed and since pitch polishers can be used, a much finer surface is obtained in the finished lenses than 40 when only one polisher formed of other material would be used. Nor is the invention limited to the number of cam elevations or depressions, as that may be modified to suit the desire of the builder of the machine. 45

The invention claimed is:

1. A machine for polishing lenses, including a frame, a shaft mounted in said frame, a spotting wheel thereon for holding a series of lens blanks on the periphery thereof, a plurality of oppositely located polishers, means for holding said polishers in position to polish the lens blanks on said wheel, and means for oppositely and simultaneously reciprocating said polisher holding means 55 transversely of the spotting wheel.

2. A machine for polishing lenses, including a frame, a shaft having bearing in said frame, a spotting wheel mounted in said shaft, a rocking frame fulcrumed on said shaft bearing frame with the axis at a right angle with the axis of the shaft, means pivoted to the ends of said frame for carrying and holding polishers on the lens blanks secured on said spotting wheel, polishers on 60 said polisher holders, and means for rocking 65

said frame as the spotting wheel rotates so as to cause the reciprocation of the polishers transversely of the spotting wheel.

3. A machine for polishing lenses, including a shaft, means for driving the same, a spotting wheel secured on the shaft, a frame adapted to rock longitudinally of said shaft, polisher holders pivotally connected to said frame and adapted to apply polishers to the lenses, a cam for rocking said frame, and means for driving said cam at a different speed than the shaft.

4. A machine for polishing lenses, including a shaft, means for driving the same, a spotting wheel secured on the shaft, a frame adapted to rock longitudinally of said shaft, polisher holders pivotally connected to said frame and adapted to apply polishers to the lenses, a pulley loosely mounted on said shaft, a cam secured to said pulley for rocking said frame, and means for driving the pulley at a different speed than the shaft.

5. A machine for polishing lenses including a rotary shaft, a pulley secured thereon for driving the same, a spotting wheel 90 mounted on the shaft, polisher holders adapted to apply polishers to lenses when secured on said wheel, a frame adapted to rock longitudinally on the shaft for giving the polisher holders reciprocatory movement transversely on the wheel, a pair of rollers on said rocking frame at opposite sides of the shaft, a pulley loosely mounted on said shaft, and an annular cam on said loose pulley projecting therefrom and surrounding said shaft and engaging said rollers on the rocking frame for rocking the same.

6. A machine for polishing lenses including a rotary shaft, a pulley secured thereon for driving the same, a spotting wheel mounted on the shaft, polisher holders adapted to apply polishers to lenses when secured on said wheel, a frame adapted to rock longitudinally on the shaft for giving 105 the polisher holders reciprocatory movement transversely on the wheel, a pair of rollers on said rocking frame at opposite sides of the shaft, a pulley loosely mounted on said shaft, an annular cam on said loose 110 pulley projecting therefrom and surrounding said shaft and engaging said rollers on the rocking frame for rocking the same, and means for driving said cam pulley at a different speed from the shaft pulley.

7. A machine for polishing lenses including a rotary shaft, a spotting wheel carried thereon, polisher holders for holding polishers against lenses secured on said spotting wheel, a frame adapted to rock longitudinally of said shaft for giving said polisher holders differential movement transversely of the wheel, and a rotary annular cam surrounding said shaft and engaged by said frame at diametrically opposite points there- 125 130

of, said cam having a series of gradual elevations and depressions for rocking said rocking frame.

8. A machine for polishing lenses including a rotary shaft, a spotting wheel carried thereon, polisher holders for holding polishers against lenses secured on said spotting wheel, a frame adapted to rock longitudinally of said shaft for giving said polisher holders differential movement transversely of the wheel, and a rotary annular cam surrounding said shaft, said cam having gradual elevations and depressions with an elevation diametrically opposite each depression for rocking said rocking frame.

9. A machine for polishing lenses including a frame, a rotary shaft, a spotting wheel mounted on the shaft for carrying the lenses to be polished, a plurality of polishers, polisher holders for holding the polishers

against the lenses on the periphery of the spotting wheel, a rocking frame including a plurality of bars fulcrumed on opposite sides of the shaft and formed into a frame, arms pivoted to each end of said rocking frame and to the polisher holders, springs tending to draw said arms toward each other, rollers carried on the rear side of said rocking frame and on opposite sides of the shaft, and a rotary cam concentric with said shaft and having a cam surface which is engaged with said pulleys at diametrically opposite points, the cam surface having a series of elevations and depressions which gradually increase on one side and correspondingly diminish on the other side of the center thereof, substantially as set forth.

In witness whereof I have hereunto affixed my signature.

LUCIAN W. BUGBEE.
